UNITED STATES PATENT OFFICE

JOSEPH M. HANDLEY, OF ORRICK, MISSOURI

PROPELLING MECHANISM

Application filed January 2, 1930. Serial No. 418,078.

This invention relates to improvements in propelling mechanism and while designed primarily for installation upon aeroplanes and other aircrafts, may be installed upon 5 submarines, and the primary object of the invention is to provide, in an aeroplane embodying two side propellers, novel means whereby these propellers may be tiltably adjusted so as to steer the aeroplane in an 10 upward or downward direction, and at any desired angle.

Another object of the invention is to provide a common driving means for both of the side propellers, and a novel means for 15 supporting the shafts of the propellers and the drive shafts from which the propeller shafts are driven, so as to avoid vibration and insure of smooth and even rotation of the propellers.

20 This invention also consists in certain other features of construction and in the combination and arrangement of the several parts, to be hereinafter fully described, illustrated in the accompanying drawings and 25 specifically pointed out in the appended claim.

In describing my invention in detail, reference will be had to the accompanying drawings wherein like characters denote 30 like or corresponding parts throughout the several views, and in which:

Figure 1 is a view partly in top plan and partly in horizontal section, illustrating the 35 operating and control means of the invention, and the propellers driven and controlled thereby.

Figure 2 is a view in side elevation of the fore-part of an aeroplane, a part being broken away, the view illustrating one of the 40 side propellers, and the manner in which these propellers may be adjusted.

Figure 3 is a detail horizontal sectional view illustrating the manner in which the propeller shafts are mounted as also the 45 shaft by which they are driven, and the manner in which the bearings of these shafts are constructed and braced.

Figure 4 is a vertical transverse sectional view on the line 4-4 on Figure 3 looking 50 in the direction indicated by the arrows, and

illustrating the bearing for the inner end of each propeller driven shaft.

Figure 5 is a similar view on the line 5-5 of Figure 3.

Figure 6 is a similar view on the line 6-6 of Figure 3.

Figure 7 is a view in side elevation of the gear casing in which the gearing for driving the propellers is housed.

Figure 8 is a detail view in rear elevation 60 of the structure shown in Figure 7.

Figure 9 is a horizontal sectional view through the gear casing and illustrating a somewhat different arrangement of gears 65 from that shown in Figure 3.

Figure 10 is a plan view of a submarine equipped with the invention.

In the drawings and referring more particularly to the embodiment of the invention in an aeroplane or other aircraft, the body 70 of the plane is indicated by the numeral 1 and the usual front propeller by the numeral 2, this propeller being driven by a suitable multi-cylinder engine (not shown) the crank shaft of the engine being indicated 75 by the numeral 3.

Side planes, which, with their driving and control means, constitute the present invention, are indicated by the numeral 4 and 80 these planes are driven from the crank shaft 5 of another multi-cylinder engine (not shown) by means which will presently be described. Openings 6 are provided in the opposite sides of the fore-part of the aeroplane body 1 and mounted within each of 85 these openings is a bearing, indicated in general by the numeral 7. This bearing is preferably of the customary type embodying a base section indicated by the numeral 8, and a cap section indicated by the numeral 9, which latter section is secured to the base 90 section by a bolt 10. A sleeve 11 is journaled at one end in each bearing 7, and each sleeve is provided with an enlarged hollow cylindrical end 12 at its inner end, and with a collar 13 which is spaced with respect to the inner end of the enlargement 12 and the inner end of the enlargement and the 95 said collar abut the opposite sides of the respective bearing 7 so as to prevent longi-

- tudinal displacement of the sleeve. Each end of the crank shaft 5 is provided with a circular head 14 and a similar head 15 is fitted to the inner end of a shaft 16 which constitutes an alined extension of the crank shaft and means for transmitting power to a respective one of the side propellers. The inner end of each shaft 16 is preferably squared as indicated by the numeral 17, and the end of the crank shaft 5 with which it is associated is provided with a squared socket to receive this end of the shaft 16, and bolts 18 are secured through the heads 14 and 15, and thus serve to connect the crank shaft 5 and shaft 16, the head 15 being preferably provided with a hub 19 and a pin 20 being fitted through alined openings in the hub and in the squared portion 17 of the shaft 16.
- 20 The enlargement 12 of the sleeve 11 is interiorly threaded as indicated by the numeral 21 and a bushing 22 is threaded to fit within this end of the enlargement and serves to retain in place, within the enlargement, a roller bearing race, which is indicated by the numeral 23.
- 25 The sleeve 11 is interiorly of a diameter to receive the shaft 16 and in order that the sleeve may be supported for rotative adjustment to provide for tilting of the propellers, by a means which will presently be described, the outer end of the sleeve is mounted in a bearing, which is indicated by the numeral 24 and which includes a section 25 mounted upon the outer end of a bracket arm 26, which is provided with a right angularly turned inner end 27 secured by means of bolts 28 to the respective side of the body of the aeroplane. The bracket arm 26 constitutes the horizontal arm of a substantially V-shaped bracket, the other arm of which is indicated by the numeral 29 and extends downwardly and inwardly at an acute angle from the arm 26, and is secured by an attaching portion 30 to the body of the aeroplane near the lower side thereof. The bracket frame comprising the members 26 and 29 serves to brace the respective sleeve 11 when the respective propellers 4 are adjusted to the horizontal position shown in dotted lines in Figure 2 of the drawings and, in order to brace the outer bearing 24 against rearward displacement, when the propellers are in a vertical position such as shown in Figures 1, 2 and 3, a brace bar or strut 31 is secured at its forward end as at 32 to the rear side of the bearing 24 and extends rearwardly and inwardly, and is secured at its rear end as at 33 to the respective side of the body of the aeroplane.
- 35 Mounted in each bearing 24 is the outer end of the respective sleeve 11 and a collar 34 is formed upon this end of the sleeve and 40 constitutes an abutment to engage the inner side of the bearing 24, and this end of each sleeve is integral with one section 35 of a gear casing which is indicated by the numeral 36 and comprises also an outer section 37 which is separably connected with the section 35 by the provision of flanges 38 upon the sections and the passage of bolts 39 through these flanges. The section 35 of the gear casing 36 is provided with a cylindrical portion located centrally of the outer side of said section, and this portion is indicated by the numeral 40 and within the same and surrounding the outer end of the shaft 16 is a conical roller bearing race 41. A bevel gear 42 is fixed upon the outer end of each shaft 16 and meshes with a bevel gear 43 which is keyed upon the inner end of a shaft 44 journalled in bearing portions formed in the two sections 35 and 37 of the casing 36, at the forward side of 45 said casing. A conical roller bearing race 45 is arranged within the forward side of the gear casing 36, and in front of the bevel gear 43 so as to provide against any displacement of the said gear 43 with respect to the gear 42. The rear end of the shaft is mounted in a bearing socket 46 formed by the meeting sides of the casing 36 at the rear thereof, and a conical roller bearing race 47 surrounds this end of the shaft and minimizes the thrust imposed upon the shaft by rotation of the propellers 4.
- 50 In order that the propellers may be tiltably adjusted so as to provide for straight forward flight of the aeroplane or upward or downward flight at any desired angle, means is provided which will now be described. The means referred to comprises a U-shaped frame indicated in general by the numeral 48 and including side members 49 and 50 and a connecting member 51, this latter member being provided with a segmental worm gear indicated by the numeral 52. The ends of the side members 49 and 50 are fitted and secured to the sleeve 11 at the enlarged inner ends 12 thereof and at this point it will be understood that inasmuch as the gear casing 36 for the driving gears of each propeller is integral with the respective sleeve 26, swinging of the frame 48 will result in rotative adjustment of the sleeves and tilting of the propellers. In order that such swinging movement of the frame may be effected, a steering post 53 is mounted in upwardly and rearwardly inclined position within the body of the aeroplane in rear of the gear 52 and is provided at its lower end with a worm 54 which meshes with the teeth of the roller segment 52 and it will be evident that the pilot of the aeroplane, by rotating this shaft through the medium of the usual hand wheel, (not shown) which is ordinarily employed will cause such shaft to be adjusted to cause the propellers 4 to assume the full line position

shown in Figure 2 or any position between this position and the dotted line position shown in Figure 2.

In mounting the propellers 4, each shaft 44 is provided with key-ways 55 at its forward end and the propeller hub 56 is fitted onto this end of the respective shaft, and keys 57 are fitted into the key-ways and serve to connect the hub with the shaft, a head 58 being fitted onto the outer end of each shaft and connected with a head 59, which is formed upon the inner end of the hub by bolts 60, a nut 61 being fitted onto the extreme outer end of the shaft 44, which end is threaded, and a cotter pin 62 is fitted through this end of the shaft after the bolt has been tightened.

Figure 9 of the drawing illustrates a modification of the gearing for transmitting motion from the shafts 16 to the shafts 44 and in this figure, the parts which correspond to the parts shown in Figure 3 are indicated by corresponding reference numerals primed, and in this modified form, as will be observed by reference to Figure 9, the conical roller bearing races 45 and 47 may be dispensed with inasmuch as the gear 43' which corresponds to the gear 43 is in mesh with the gear 42', corresponding to the gear 42, at the rear side of the latter gear and therefore the forward pull exerted by the propeller serves to firmly hold the gear 43' in mesh with the gear 42.

Figure 10 of the drawing illustrates the embodiment of the invention in a submarine, the body of which is indicated by the numeral 64 and side propellers indicated by the numeral 65 are arranged at opposite sides of the said body 64 near the front and rear ends thereof, and also intermediate the ends of the body and are driven in the same manner and controlled in the same manner, and by the same means as that previously described.

The invention contemplates the adaptation of the principles thereof in the construction of aeroplanes, zeppelins, and marine craft.

What I claim is:

In a propelling mechanism of the class described, the combination with the body to be propelled, of a motor rotated crank shaft mounted transversely in the body, tubular housings mounted for rotative adjustment at opposite sides of the body and in axial alinement with the crank shaft, a gear case at the outer end of each housing and adjustable therewith, a shaft mounted in each housing and connected with the respective end of the crank shaft for rotation therewith, a propeller shaft mounted in each gear case, operative gear means connecting at each side of the gear system the last mentioned shafts, a propeller upon each of the propeller shafts, a frame within the

body to be propelled, the frame comprising side members and a member connecting corresponding ends of the side members, means connecting the other ends of the side members with the inner ends of respective ones of the tubular housings, a segmental worm gear upon the frame, at one end thereof, and a manually rotatable worm shaft having its worm in mesh with the said worm gear and adjustable to simultaneously rotatably adjust the tubular housings, the gear cases thereon, and the propellers and thereby vary the angular positions of the propellers.

In testimony whereof I affix my signature.

JOSEPH M. HANDLEY.
